VALVE FOR BAGS

**Theron A. Contryman, Oswego, N. Y., assignor to
St. Regis Paper Company, New York, N. Y., a
corporation of New York**

Application September 21, 1938, Serial No. 231,001

13 Claims. (Cl. 229—62.5)

This invention relates to an improvement in valves for bags, and has for its object to improve the closing of the valve, reduce the danger of leakage, and strengthen the closure of the end of the bag.

The invention is particularly adapted for use in a bag having its end closed by a sewed seam. Valves in such bags are customarily extended longitudinally of the bag while the bag is empty, but are spread laterally of the bag when the bag is filled. The valve closes most securely against leakage when the change in shape of the valve from its empty-bag position to its filled-bag position takes place about definite, predetermined fold lines, so that the closing lip of the valve lies smoothly against the end of the bag. One object of the invention is to facilitate this desired closing of the valve.

The valve corner of a bag is sometimes torn during, or at the close of, the filling operation. One of the objects of the invention is to increase the resistance of the valve corner to tearing without increasing the amount of material in the bag.

The manner in which the objects of the invention are achieved will appear as the description proceeds.

In the accompanying drawing, forming a part of this specification,

Figure 1 is a view of one corner of a bag with its sides spread apart and the corner turned in to form a valve;

Fig. 2 shows the edges folded to embody the improvement herein claimed;

Fig. 3 is a view of the corner of the bag after the valve has been tucked in and the end closed, the bag wall being broken away to show the valve;

Fig. 4 is a section along the line 4—4 of Fig. 3, and showing the edge of the valve;

Fig. 5 is a view similar to Fig. 4, but showing the valve in partially closed position; and

Fig. 6 is a view similar to Fig. 3, but showing a modification of the manner of folding.

In the embodiment of the invention illustrated in the drawing, a gusseted bag tube 10 is spread apart and the corner 11 turned in, as usual, to form a valve flap 12. In the form shown, the edge of the valve flap is provided with slots 13 and 14. Originally, the corner where the valve is to be formed extends beyond the adjacent end of the bag walls, so as to provide an extended valve flap.

The improvement is produced by folding under corner 15 about diagonal line 16, and corner 17

about diagonal line 18, as shown in Fig. 2. When the sides of the bag are brought together and the end is closed by a seam 25, as shown in Figs. 3, 4 and 5, folded back portions 15 and 17 are caught in the seam and increase the wall thickness at this point.

The usual manner of filling such a bag is to hang it on a filling tube which is inserted through the valve opening. When the bag is filled, it places considerable stress upon the seam above the filling tube, and the bag sometimes yields to this stress. Turning back the edge of the valve lip, as described, not only provides an extra thickness at the point where the stress is greatest, but also provides a fold at the edge of the valve at the seam, thereby increasing the resistance to tearing stress.

Also fold lines 16 and 18 increase the resistance of the valve flap to bending along these lines. 20 When the bag is empty, the valve collapses as shown in Figs. 3 and 4; but when the bag is filled, the walls of the bag spread and the lower edge of the valve flap is pressed upward towards the closing seam by the contents of the bag. 25 Fig. 5 shows the valve in a partly closed position.

The valve is least likely to leak when the lower flap lies smoothly against the upper flap. It will be readily understood that the stiffened fold lines 16 and 18 increase the tendency for the flap to bend along lines 13 and 14 when the under flap is pressed upward, and decrease the danger of irregular crumpling of the edge of the valve. In fact, lines 16 and 18 act somewhat as stiffening rods, compelling the flap to bend along lines 13 and 14 as hinges, which are approximately half-way between seam 25 and middle line 26 of the valve.

It will be seen, therefore, that turning back corners 15 and 17 as described strengthens the 40 valve corner and also aids in proper closure of the valve.

Folding back corners 20 and 22 about lines 21 and 23 respectively stiffens the flap along lines 21 and 23 and causes these lines to act as toggles 45 from fold line or hinge 26, spreading apart the hinges 13 and 14 when the lower flap is pressed upward, and decreasing the danger of buckling and irregular crumpling of the lower lip of the valve.

50 It is preferred to fold the corners of the valve away from the filling opening as shown. Some of the objects of the invention would be accomplished by folding the valve edges into the filling passage, but this is not preferred because the infolded edges may catch on the filling tube, and

in any case have a tendency to form leakage openings where the ends of the folds occur.

Instead of folding corners 15 and 17 about diagonal lines 16 and 18, they may be folded about lines parallel with the edge of the flap. In Fig. 6, corner 15' is shown folded about line 16' in this way. Corner 20' may be left unfolded, as shown, or may be folded about a continuation of line 16', or about any other line as desired. The type shown in Fig. 6 has the advantage of easy folding and of extending the folded corner farther into the seam, for strengthening purposes.

Under some circumstances, in a multi-ply bag, only part of the plies need be folded. It will be readily understood that other changes in the shape of the valve and folded back corners may be made, and that such folds may be made at only part of the places indicated while retaining some advantages, and that various other departures may be made from the exact disclosure, the scope of the invention being indicated by the appended claims.

What I claim is:

1. A bag having a corner turned in to form a valve flap and having the central portion of the flap extending straight into the bag for the full length of the flap and having the corners of the flap turned back and providing fold lines along the inner edge of the flap at each side of said central portion.

2. A bag having a corner turned in to form a valve flap and having a sewed seam closing the valve end of the bag, and the corners of the valve flap being turned under between the flap and the side wall of the bag and caught in the seam, thereby providing an extra thickness in the seams at the top of the valve.

3. A bag having a corner turned in to form a valve flap, the valve flap being shaped to close normally by folding about predetermined lines perpendicular to the inner edge of the flap, and having part of the edge of the flap turned back and forming a fold at the edge of the completed flap, said fold terminating at one end at one of said predetermined lines.

4. A bag having a corner turned in to form a valve flap, a sewed seam closing the end of the bag, the valve flap being shaped to close normally by folding about predetermined lines approximately parallel with the seam and midway between the seam and the center of the flap, and the corners of the flap being turned back toward the end of the seam, the lines about which the corners are folded forming the final edge of the valve flap running from the seam to, and terminating at, said predetermined lines.

5. A bag having a corner turned in to form a valve flap, a sewed seam closing the end of the bag, and the corners of the valve being turned in

at the seam and about lines running diagonally from the seam to the inner edge of the flap.

6. A bag in accordance with claim 5, and having said lines terminate at the edge of the valve approximately half way between the seam and the middle of the inner edge of the valve flap.

7. A bag in accordance with claim 5, and having said lines terminate at the edge of the valve flap approximately half way between the seam and the middle of the valve, and having the edges of the flap turned back about lines running from the edge of the valve at its middle point diagonally backward to a point approximately half way between the seam and the middle of the valve.

8. A bag having a corner turned in to form a valve flap, a sewed seam closing the end of the bag, and each corner of the valve being turned in at the seam about a line running approximately parallel with the edge of the flap and for approximately half, and only approximately half, the distance between the seam edge of the flap and the central line of the flap.

9. A paper bag having a valve flap that closes best when folded about predetermined lines approximately perpendicular to the inner edge of the flap, and having the edge of the flap folded back about a line running approximately at a right angle to, and terminating at, one of the first said lines.

10. A bag in accordance with claim 8 and having the last said line terminate at the inner edge of the valve closely adjacent one of the first said lines.

11. A multi-ply bag having a corner turned in to form a valve flap, and having the central portion of the flap extending straight into the bag for the full length of the flap and having at least one of the plies at the corner of the flap turned back along a line running in the general direction of the edge of the flap.

12. A bag having a corner turned in to form a valve flap, a sewed seam closing the end of the bag, the valve flap being shaped to close normally by folding about predetermined lines perpendicular to the inner edge of the flap and the corners of the valve being turned in at the seam and about lines running diagonally from the seam to the inner edge of the flap.

13. A bag having a corner turned in to form a valve flap, a sewed seam closing the end of the bag, the valve flap being shaped to close normally by folding about predetermined lines perpendicular to the inner edge of the flap and the corners of the valve being turned in at the seam and about lines running diagonally from the seam to the inner edge of the flap at a point about half way between the seam and the middle of the flap.

HERON A. CONTRYMAN.

CERTIFICATE OF CORRECTION.

Patent No. 2,307,111.

January 5, 1943.

HERON A. CONTRYMAN.

It is hereby certified that error appears in the printed specification of the above numbered patent requiring correction as follows: Page 2, second column, line 30, claim 10, for "claim 8" read --claim 9--; and that the said Letters Patent should be read with this correction therein that the same may conform to the record of the case in the Patent Office.

Signed and sealed this 16th day of February, A. D. 1943.

Henry Van Arsdale,
Acting Commissioner of Patents.
